UNITED STATES PATENT OFFICE.

WILLIAM A. TROUT, OF LOS ANGELES, CALIFORNIA.

CIRCULATING HEAD.

Application filed October 15, 1923. Serial No. 668,696.

This invention relates to circulating heads, and particularly to a circulating head that is advantageous when it is desired to cement off well casing or tubing. The invention 5 lends itself to various adaptations other than the cementing process, and has for its object the provision of a circulating head which is capable of withstanding great pressure without leakage and still render access with- 10 in the circulating head an easy matter.

With the present type of circulating head through which neat cement is forced, the back pressure sometimes is so great as to cause leakage through such head, and the 15 present invention is so formed with its parts so inter-related that all discharge or leakage through the head is overcome.

In practicing the invention I may provide a body adapted for attachment with casing 20 with the said body formed with circulation openings within which circulating pipes may be attached with one end zone of such body flanged and provided with a breech lock adapted to accommodate a breech lock 25 cap. The cap is formed to carry an annular gasket, one face of which may be inclined with such face adapted to cooperate with a beveled portion of the body. When the cap is in position and locked to the body the 30 inner surface of the annular gasket is substantially flush with the inner surface of the body member. Back pressure against the cap and the body will only tend to tightly wedge or expand the gasket against the 35 beveled surface of the body and thus prevent leakage between the cap and the body. By forming the body of a size corresponding to the size of the casing and providing a readily detachable cap, it is possible to quickly re- 40 move the cover and insert the usual wooden plugs or wooden plug in the body, replace the cap, force cement within the casing through the circulating head until the casing is filled, remove the cap and place within the 45 circulating head a second wooden plug and then continue the forcing process by water or other fluid and force the second plug downwardly, thus forcing the cement up around the outside of the casing and against the 50 wall of the well hole. Upon removal of the cap the usual drilling tools may be inserted within casing to cut away the wooden plugs without removing the body.

With the above and other objects in view 55 the invention consists in the novel and useful provision, formation, construction, as-

sociation and relative arrangement of parts, members and features, all as shown in one embodiment in the accompanying drawing, described generally and finally pointed out 60 in claim.

In the drawing:

Figure 1 is a vertical sectional view of the improved circulating head with the various parts shown in cooperative position, and 65 with a fragment of casing joined with the body of such circulating head; and

Figure 2 is a top plan view of the circulating head.

Referring with particularity to the drawing, the circulating head is designated as an 70 entirety and in one embodiment by A, and casing adapted for jointure with said circulating head is designated by B. The circulating head includes a body member *a* and 75 a cap member *b*, which cap member is adapted to carry a seal or gasket *c*. The body member *a* may be internally threaded as shown at 1 whereby the casing B may be joined therewith. Said body member is likewise provided with transverse taper threaded openings 2 and 3 adapted to have screwed 80 therein circulation pipes 4 and 5. The body *a* is annular in formation and an end portion 85 thereof is inclined upwardly and outwardly as shown at 6 from a surface 7 of such body, and said body has one end terminating in a breech lock 8, which consists in providing a series of segmental spaced flanges 9, forming 90 a part of the wall 10. It will be noted upon reference to Figure 1 that a ledge 11 is included between the inner surface of the wall 10 and the termination of the inclined or beveled wall 6. The cap *b* includes 95 a dome portion 12 terminating in an annular flange 13, the said flange being provided with a series of spaced segments 14. It is to be noted that the segments 14, as well as a portion of the annular flange 13 is adapted 100 to rest upon the ledge 11 of the body, and that when the cap is properly turned the segments 14 of the cap will interlock with the segments 9 of the body, as shown both in Figures 1 and 2 at 15. The annular flange 13 of the cap is provided with an annular recess, as shown at 16 within which is accommodated in part the seal or gasket 105 *c*, which seal or gasket may be substantially right triangular in cross section, with its inner annular surface as 17 forming one leg of the triangle and hypotenuse or inclined surface 18 adapted to contact with the be- 110

eled or inclined surface 6 of the body. The base of such seal, as shown at 19 is fitted within the annular groove 16 of the cap. The cap may be provided with handles 20 and likewise provided with a screw-threaded bore 21 adapted to receive a pipe 22 for the relieving of pressure within the circulating head.

In actual use of the device, neat cement 10 may be forced through the pipes 4 and 5 into the body *a*, and if it is assumed that a wooden plug or other member has been inserted within the body *a* through its top opening, with the cap *b* replaced upon the body and locked, the forcing of cement 15 through the pipes 4 and 5 will force the plug downwardly within the casing *B*. When the casing has been filled to the desired point with cement, the cap *b* may be detached from 20 the body, a second plug inserted within the body and then mud or water or other fluid may be forced through the pipes 4 and 5 to force the plug downwardly upon the cement in the casing *B*. Any back pressure will 25 wedge the seal or gasket *c* against the inclined or beveled face of the body and thus prevent any leakage between the cap and the body. Furthermore, the particular formation 30 of the cap having the breech lock portions cooperating with the breech lock por-

tions of the body provides a device of great strength and is far superior to bolts and nuts. The seal *c* may be formed of various materials such as soft rubber or the like.

It is obvious that various changes and 35 modifications may be made in practicing the invention, in departure from the particular showing of the drawing, without in any manner departing from the true spirit of the 40 invention.

Having thus disclosed my invention, I claim and desire to secure by Letters Patent:

A circulating head adapted for association 45 with well casing, said circulating head including a body and a cap therefor, said circulating head being substantially annular in form with the inner surface portion of the head beveled in part, a triangular wedge-shaped flexible member carried by said cap and having one of its sides beveled to cooperate 50 with said beveled portion on said head, and its other side extending in a substantially parallel plane with said body, said cap being formed with an inwardly tapered groove for holding and locking said flexible member in operative position.

In testimony whereof, I have signed my name.

WILLIAM A. TROUT.
